(57) **CLAIM**

The ornamental design for a knit crochet bag, as shown and described.

DESCRIPTION

FIG. 1 is a side elevational view of the knit crochet bag with the cover flap in an elevated position, and it is to be understood that the other side elevational view is the same; FIG. 2 is an end elevational view with the top central zipper closed and with the top central flap over the central storage pocket;

FIG. 3 is a bottom plan view;

FIG. 4 is a top plan view illustrating the top central zipper closed and on the left the left flap elevated to illustrate three storage pockets and on the right the right flap lowered and covering the three storage pockets;

FIG. 5 is a top plan view illustrating the top central zipper in an open position and the top central flap open to disclose the central storage pocket and with the left flap covering the three left pockets and with the right flap covering the three right pockets; and,

FIG. 6 is a side elevational view with the top central zipper closed and the side flap closed and covering the three side pockets and a flap over each end pocket.

The straps in FIG. 2 are shown broken away to indicate indeterminate length.
